UNITED STATES PATENT OFFICE.

CHARLES A. RICHARDS, OF PAULLINA, IOWA.

AUTOMOBILE CAMP-TRAILER.

1,300,021.

Specification of Letters Patent. Patented Apr. 8, 1919.

Application filed May 24, 1918. Serial No. 236,405.

To all whom it may concern:

Be it known that I, CHARLES A. RICHARDS, a citizen of the United States, residing at Paullina, in the county of O'Brien and State 5 of Iowa, have invented new and useful Improvements in Automobile Camp-Trailers, of which the following is a specification.

This invention relates to an automobile camp trailer comprising a main frame or body, a collapsible structure supporting a top, a plurality of mattress frames and means for moving these frames into operative position and lifting the collapsible structure and top. The invention further 10 comprises various other features of construction hereinafter described and claimed.

In the accompanying drawings:

Figure 1 is a view in elevation showing the apparatus in operative position.

20 Fig. 2 is taken on the line 2—2 of Fig. 1, showing the main portion of the structure in top plan.

Fig. 3 is a view in side elevation, on a reduced scale.

25 Fig. 4 is a view partly in vertical section showing means for throwing the mattress frames to the outer position and means for elevating one of the canopy supporting devices.

30 Figs. 5 and 6 are details of construction described below.

The body portion of the device includes a main frame provided with a bottom member 10, a vertically extending wall 11 and another vertically extending wall 12 at the 35 opposite edge of bottom member 10, the wall last named being somewhat lower than the wall 11. An end wall 13 is provided at one end of the frame, the opposite end being 40 open.

Vertically mounted posts 14, 15, 16 and 17 are located at suitable distances from the ends of the body portion and support the upper structure. They also provide bearings for longitudinal shafts 18 and 19 carrying gear wheels 20 and each shaft being also provided with a ratchet wheel 21 engaged by a pawl 22, these shafts being designed for operation by means of a crank detachable 45 with reference thereto.

50 A plurality of mattress frames or bed frames are provided, these being designated

25 and 26 and comprising outer rails one of which is designated 27 and the other of which is shown at 28 and is somewhat lower 55 than the outer member first named. The mattress frames are designed to move inwardly over the body portion and to overlap each other when the device is in closed position. The frames mentioned include inner bars or rails 29 or 30 as the case may be and a plurality of end rails designated 31. These end rails carry rack members 32 and are cutaway longitudinally as shown at 33 for the purpose of 60 coöperating with removable guiding members 34 and 35 located at one end of the main frame, and similar members located at the opposite end thereof. Tie-rods or the like for the mattress frames are shown at 70 38. It may be added that the main frame is braced by lower transverse bars or the like designated 39 and by upwardly extending braces 40 connected with said bars and connected at their upper ends to the sides at 75 the points 41. The mattress frames are supported when in extended position by leg members 42 pivotally connected with bars 43 extending through bail members 44 carried by the outer longitudinal members of 80 the mattress frames. These members 43 extend to the side portions 11 and 12 of the main frame and are detachably connected therewith. Angle members 45 are secured at the ends of members 43 and engage straps 85 or the like designated 46.

The upper frame for supporting the top comprises longitudinal members 48 and 49 and transverse members 51. The top proper is designated 52 and is carried by the frame 90 specified. Means for supporting the upper frame comprises a plurality of members 53 and 54 at each end of the device. The upper portions of supporting bars 53 and 54 are pivotally connected with the upper frame, 95 and at a point somewhat distant from their lower ends they are pivotally connected with bars 55 and 56, the bar 55 being pivoted to bar 53 and the bar 56 being pivoted to bar 54. These lower bars 55 and 56 are pivotally 100 connected with posts 16 and 17 and bars similar to 55 and 56 at the opposite end of the device are pivotally connected with posts 14 and 15. The structure for elevating the

top and supporting the latter is the same at each end of the device and it is only necessary to describe the connections and operation at one end. Upper bars 53 and 54 carry 5 outwardly extending legs one of these being shown at 58 and the other at 59, the elements last named being secured to bars 53 and 54 at about the angle shown. Legs 58 and 59 are connected with the outer side members 10 of the mattress frames by means of bars 60 and 61, pivotal connections being provided at each end. The outward movement of the bed frames and the pull exerted on bars 60 and 61 throws the legs 58 and 59 into 15 position for elevating the top and places the members 53 and 55 in alinement and in a substantially vertical position, members 54 and 56 being also in alinement.

In order to provide for the proper operation 20 of the lifting apparatus and to prevent buckling or the like, I provide a triangular brace one member of which extends at a substantially right angle with vertical bar 55, this member being designated 63 and being 25 retained by an arm 64 extending at an angle. Pivottally connected at 67 with the outer end of element 63 is a connecting rod 65 pivoted at 66 to vertical bar 56 on the opposite side of the end structure. The connection at 67 is 30 detachable and permits the connecting rod 65 to drop into a substantially vertical position for providing easy access to the device and to the passage-way between the mattress frames when the apparatus is in position 35 for use. Member 63 and arm 64 are detachable at 64'.

A stop plate 69 mounted at 70 engages the edge portion of vertical bar 55 when the top is raised and limits the movement in that 40 direction. A similar stop plate 71 performs the same function on the opposite side of the end structure.

Each of the outer side members of the mattress frames carries a rotatably mounted 45 shaft designated 73 or 74 as the case may be and at each end thereof is mounted an upright 75 carrying a diagonal brace 76 supporting the canopy. These shafts carrying the uprights just specified are rotated for 50 the purpose of bringing the uprights into vertical position, from a horizontal position, by means of slidable connecting devices designated 79 and secured to the said shafts by any suitable device 80, and secured at 83 to 55 one of the vertical posts 14, 15, 16 or 17. Members 79 each have arms 81' at the ends thereof, these arms carrying eye members 82 slidably on the bars 82. A guiding member 83 acts also as a stop, and link 84 operates 60 arm 80 and rotates the shaft 73 or shaft 74 when the stop is engaged by the outward movement of the mattress frames. Upon the outward movement of the mattress frame the shaft is partly rotated and the upright is 65 raised into operative position. The mattress

frames may be detached, when it is desired to use the body as an ordinary truck trailer.

Suitable rollers or small wheels 81 are provided at the sides of the apparatus for permitting it to be attached by means of 70 securing devices 82 to the vehicle which is to be employed in transporting the apparatus.

Guy ropes 85 are connected at 86 and lead to stakes driven into the ground. The 75 top is secured when lowered by pivoted bars 87 engaging the forked portions of brackets 88, wing nuts 89 retaining them in position.

What is claimed is:

1. In a device of the class described, a 80 main frame, a plurality of mattress frames movable laterally with reference thereto leaving a free space between the frames when extended, means comprising a rack member and a rotatable member for moving said 85 frames to extended position, a collapsible structure and a top supported thereby, and means connected with the collapsible structure and the outer portions of the mattress frames for elevating and lowering the collapsible structure. 90

2. In a device of the class described, a main frame, a plurality of overlapping and laterally movable mattress frames supported from the main frame, means carried by each 95 mattress frame and means mounted on the main frame for extending the mattress frames, a canopy supporting device mounted on each mattress frame and adapted to be raised from a horizontal to a vertical 100 position upon the movement of the mattress outwardly, a top for the main frame, collapsible means for supporting the top, and means connected with the outer portion of each mattress frame and with the collapsible 105 structure for elevating the latter.

3. In a device of the class described, a main frame, a plurality of mattress frames movable laterally with reference thereto, a top, a collapsible structure for supporting the top, a canopy supporting device connected with each mattress frame, and means for elevating the collapsible structure, and means for elevating the canopy support upon movement of each mattress frame outwardly 115 from the main frame.

4. In a device of the class described, a main frame, a top, a collapsible structure for supporting the top including a plurality of bars pivotally connected, a plurality of vertical posts supported by the main frame, means for connecting certain of the bars first named with said posts, laterally extending legs carried by others of said bars first named, and means for moving said legs 120 for elevating the collapsible structure and throwing certain of the bars pivotally connected with each other into a substantially vertical position. 125

5. In a device of the class described, a 130

main frame, a plurality of mattress frames movable laterally with reference thereto, a top, a collapsible structure for supporting the top, a canopy supporting device connected with each mattress frame, and including a rotatable shaft and radial arms thereon, means for elevating the collapsible

structure, and means for elevating the canopy support upon movement of each mattress frame outwardly from the main ¹⁰ frame.

In testimony whereof I affix my signature.

CHARLES A. RICHARDS.
